RAIL HOLDING DEVICE

Jacob Rush Snyder, Cleveland, Ohio

Application November 8, 1946, Serial No. 708,594

13 Claims. (Cl. 238—349)

1

This invention relates to rail fastenings of the type in which a railway rail is yieldingly held against a support and, as one of its objects, aims to provide an improved fastening of this kind requiring relatively few parts which are adapted to be economically manufactured and installed.

Another object of this invention is to provide an improved rail fastening which, although of a simple and inexpensive construction, will safely hold a rail in the desired position for a prolonged period of service and in a manner which will result in a minimum amount of deterioration of the tie.

Still another object of the present invention is to provide an improved rail fastening embodying a two-piece clamp and a load spring, and wherein one of the clamp pieces is rockable on a fulcrum formed by the other piece for yieldingly applying the load of the spring to the rail flange.

A further object of this invention is to provide an improved rail fastening embodying upper and lower clamp pieces and a loading spring, and wherein the upper piece applies the load of the spring to the rail flange and the lower piece applies the load of the spring to the tie plate and also forms a fulcrum on which the upper piece is rockable.

Yet another object is to provide an improved rail fastening of the character mentioned in which the fulcrum forming piece of the two-piece clamp is of a novel construction and cooperates with the tie plate or with the rail flange in a manner to prevent turning of the clamp about the stem of the fastening member.

The invention can be further briefly summarized as consisting in certain novel combinations and arrangements of parts hereinafter described and particularly set out in the appended claims.

In the accompanying sheets of drawings

Fig. 1 is a plan view showing two identical rail fastenings embodying the present invention and wherein portions of one of the fastenings are broken away;

Fig. 2 is a sectional view taken on line 2-2 of Fig. 1 and in which one of the two fastenings is shown in vertical section and the other is shown in elevation;

Fig. 3 is a detached perspective view showing the upper member of the two-piece clamp;

Fig. 4 is a similar detached perspective view showing the lower member of the two-piece clamp;

Fig. 5 is a plan view of a modified rail fastening embodying this invention;

Fig. 6 is a vertical sectional view taken therethrough on line 6-6 of Fig. 5;

Fig. 7 is a detached perspective view showing the lower member of the two-piece clamp embodied in this fastening;

Fig. 8 is a plan view showing another modified form of rail fastening embodying this invention;

Fig. 9 is a vertical sectional view taken therethrough on line 9-9 of Fig. 8 and;

Fig. 10 is a detached perspective view showing the lower member of the two-piece clamp embodied in this fastening.

In the form of the invention illustrated in Figs. 1 and 2 there is shown a wood tie 12 having a tie plate 13 thereon and a railway rail 14 resting on the tie plate. The rail is of a conventional type having a head 14a and a base flange 14b. The tie plate 13 may also be of a conventional form and is here shown as being a substantially rectangular metal plate having thickened edge portions 15 extending substantially parallel with the rail and such thickened portions having a substantially flat top surface 16. The inner or adjacent edges of the thickened portions 15 form rail gauging shoulders 17 which extend along the edges of the base flange 14b. The tie plate 13 also has suitable openings 18, in this instance three such openings, extending therethrough adjacent the shoulders 17. The intermediate portion of the tie plate can be of substantially uniform thickness as here shown, in which case a desired inclination of the rail 14 can be obtained by providing the tie 12 with a sloping recess 19 therein in which the tie plate is located as shown in Fig. 2.

The improved rail fastening also includes a fastening member 21, a two-piece clamp comprising upper and lower members or pieces 22 and 23, and a load applying spring 24. When the tie 12 is a wooden tie as here shown the fastening member 21 is preferably in the form of a screw spike having a threaded stem portion 21a screwed into the tie and a plain or unthreaded stem portion 21b projecting upwardly from the tie through the substantially circular tie plate opening 18. The spike is provided at its upper end with a head 25 which is located a substantial distance above the flat surface 16 of the tie plate 13. The head 25 has a shoulder 25a on the underside thereof and a polygonal top portion 25b to which a wrench or the like is adapted to be applied.

The upper piece 22 of the two-piece clamp is a plate-like member or part which can be constructed from sheet metal or plate stock by suitable stamping for forming operations. The piece

22 has an opening 22a therein through which the plain stem portion 21b of the fastening member extends and is of a length such that its inner end overlaps the base flange 14b of the rail 14. The inner end of the clamp-piece 22 can be curved or bowed as shown in the drawings so as to provide a rounded bearing portion 26 adapted for a rockable holding engagement with the top surface of the base flange 14b. The outer end of the clamp-piece 22 has a bearing portion or projection 27 of reduced width thereon which is engageable in a fulcrum recess 28 provided on the lower clamp-piece 23. The reduced bearing portion 27 can be obtained on the clamp-piece 22 by notching out the corners of the outer end of this piece, as indicated at 29 in Fig. 3.

The lower piece 23 of the two-piece clamp comprises a chair-like angular member or clip constructed from sheet metal or plate stock by suitable stamping or forming operations. This piece includes a laterally extending plate portion 30 which under-lies the upper piece 22 and has an opening 30a therein through which the stem portion 21b of the fastening member extends. The lower piece 23 also includes an upturned substantially flat portion 31 which extends along the stem of the fastener on the side thereof remote from the rail 14.

The upturned portion 31 is provided at its lower edge with a substantially straight seat portion 32 adapted to rest on the flat surface 16 of the tie plate 13. The upper edge of the upturned portion 31 forms a support and fulcrum for the outer end of the upper clamp-piece 22 and contains the fulcrum recess 28 in which the bearing projection 27 is received. The seat portion 32 of the upturned portion 31 is formed by metal which is deflected or displaced from one side of the opening 30a during the shaping of this piece to the angular form shown in the drawings. The fulcrum recess 28 is located between a pair of upstanding lugs 33 which engage in the corner notches 29 of the outer end of the upper clamp-piece 22 when the latter is assembled on the lower piece as shown in Fig. 2 of the drawings.

The stem portion 21b of the screw spike 21 is of a length such that the shoulder 25a of the head 25 will be located a substantial distance above the upper piece 22 when the two pieces of the clamp are in their assembled position. The coil spring 24 is disposed around the stem portion 21b with its lower end seating on the upper piece 22 and is subjected to compression by the head 25 so that the piece 22 will apply a yieldable holding force to the base flange 14b of the rail and the lower piece 23 will yieldingly apply a force to the tie plate 13 tending to hold the same against the tie 12. The height of the upturned portion 31 of the lower piece 23 can be varied in different specific fastenings of this construction but is preferably such that the upper piece 22 will initially be in a downwardly and inwardly inclined position as shown in Fig. 2.

The upper piece 22 is held from turning about the stem portion 21b of the fastening member by the engagement of the bearing portion 27 in the fulcrum recess 28 and the lower piece 23 is, in turn, held from swinging or rotating about the spike. Such holding of the lower piece from turning on the spike is accomplished by providing the laterally extending portion 30 thereof with downwardly deflected lugs 35 at the sides thereof of which are engageable with the edge of the base flange 14b at longitudinally spaced points

thereof. The edge portion 30b lying between the downwardly deflected lugs 35 can be deflected upwardly, as shown in Figs. 2 and 4, so as to extend in spaced overlying relation to the base flange 14. This intermediate section 30b forms an arcuate strip-like portion which extends around and engages the inner edge of the stem portion 21b of the fastening member for preventing outward shifting of the lower piece 23 while the engagement of the down turned lugs 35 with the edge of the base flange prevents rotation and inward shifting of the lower piece.

In assembling the fastening above described, the upper and lower pieces 22 and 23 of the two-piece clamp are placed in superposed relation with their openings substantially aligned with the opening 18 of the tie plate. The screw spike 21, with the spring 24 thereon in surrounding relation to the stem portion 21b, is inserted through the aligned openings and screwed into the tie 12. The screw spike is initially screwed into the tie for a distance which will cause the convolutions of the spring 24 to be compressed to a closed or solid condition along the outer edge of the spike, that is to say, at a point immediately above the fulcrum recess 28. Because of the inclined position of the upper piece 22 the convolutions of the spring at the opposite side of the spike will remain in spaced-apart relation.

The compressing of the spring convolutions to such a solid condition at the outer side of the spike forms a stop by which the driving of the spike into the tie for the correct distance is assured during the assembly operation and overloading of the clamp or stripping of the spike from the tie opening is avoided. When the fastening has been installed in this manner and a few trains have passed over the rail 14, some settling of the tie plate 13 will occur and thereafter a desired small space will also exist between the adjacent spring convolutions at the outer side of the spike. Since the outer end of the upper piece 22 is fulcrumed, the maximum swinging movement of this piece will occur at its inner end due to rising and falling of the rail during the passage of trains thereover and this swinging movement will be accommodated by the spacing of the spring convolutions at the inner side of the spike.

From the construction above described it will be seen that an improved rail fastening has been provided having a relatively small number of parts adapted to be economically produced and assembled. It will also be seen that the upper piece of the two-piece clamp is rockable on a fulcrum formed by the lower piece and applies the load of the spring 24 to the rail flange in a manner to effectively hold the rail against the tie plate and, at the same time, the lower piece applies the load of the spring to the tie plate for holding the latter against the tie so that damage to the tie by pounding of the tie plate thereon will be minimized.

Figs. 5 and 6 show a modified form of the above described rail fastening in which a conventional tie plate 31 of a different specific form is employed. The tie plate here shown has an upstanding rail-gauging shoulder 38 thereon and has an opening 39 therethrough which includes a rectangular extension 39a intersecting the shoulder 38. The fastening also includes a two-piece clamp comprising an upper piece 40 and a lower piece 41. The upper piece 40 is similar to the upper piece 22 above described but differs therefrom by reason of the fact that it has a downwardly curved bearing portion 40a at its

inner end which bridges over the upstanding shoulder 38, as shown in Fig. 6.

The lower piece 41 is generally similar to the lower piece 23 above described but differs therefrom in that the intermediate section of the laterally extending portion 42 is deflected downwardly so as to form a depending rib or lug 43 which is engageable in the square extension portion 39a of the tie plate opening 39. The engagement of the depending rib 43 in the extension opening 39a holds the lower piece 41 from turning about the stem of the fastener or screw spike 44. In other respects, this modified form of rail fastening is the same as the rail fastening shown in Figs. 1 and 2 and described above and functions in substantially the same manner.

Figs. 8 and 9 show another modified form of the improved rail fastening and which is of substantially the same construction as the fastening shown in Figs. 5 and 6 but differs therefrom in that the square extension 45a of the tie plate opening 45 extends in a direction away from the rail and the lower piece 46 of the two-piece clamp has a depending lug 47 at the lower edge of the upright portion 46a thereof which engages in this extension opening for holding the lower piece against turning about the screw spike 48.

Although different specific forms of the improved rail fastening have been illustrated and described herein in some detail, it will be understood of course that the invention is not to be regarded as being limited thereby but includes all variations and changes coming within the scope of the appended claims.

Having thus described my invention, I claim:

1. In a fastening for a rail having a base flange, a two-piece clamp comprising a lower clamp member having a fulcrum portion thereon and an upper clamp member rockable on said fulcrum portion and having a bearing portion in overlapping engagement with said flange, said upper and lower clamp members having substantially aligned openings therethrough, a fastening member extending through said openings, and a spring on said fastening member and acting on said upper clamp member to apply downward pressure therethrough to said flange, said lower clamp member being of a shape such that the fulcrum portion thereof is located wholly on the side of said fastening member remote from said rail.

2. In a rail fastening, a supporting structure, a rail having a base flange resting on said supporting structure, a fulcrum member seated on said structure adjacent said base flange and having an opening therethrough and a fulcrum portion located wholly on the side of said opening remote from said rail, a retaining member having its inner end in overlapping engagement with said base flange and its outer end fulcrumed on said fulcrum portion, said retaining member having an opening therein overlying the opening of said fulcrum member, a fastening member connected with said supporting structure and having a stem portion extending through the openings of said members and a holding portion spaced above said fulcrum portion, and a spring surrounding said stem between said holding portion and said retaining member and acting on an intermediate portion of the latter to yieldably press the retaining member against said fulcrum member and base flange.

3. In a rail fastening of the character described, a tie, a tie plate on said tie and having

an opening therein, a rail having a base flange resting on said tie plate, a screw spike having a stem extending into the tie through the opening of said tie plate and a head spaced above the tie plate, a two-piece clamp comprising a lower clamp member seated on the tie plate and an upper clamp member having one end fulcrumed on said lower clamp member and its other end bearing on the top surface of said base flange, 10 said lower clamp member having an upstanding fulcrum portion located wholly on the side of said stem remote from said rail and on which said one end of the upper clamp member is fulcrumed, said upper and lower clamp members having substantially aligned openings through which said stem extends, and a spring surrounding said stem and engaging an intermediate portion of the upper clamp member so as to apply a load to said upper clamp member for yieldingly holding said base flange against said tie plate, said spring also acting on said tie plate through said upper and lower clamp members for holding tie plate against the tie.

4. In a rail fastening, a tie, a tie plate on said tie and having an opening therein, a rail having a base flange resting on said tie plate, a screw spike having a stem extending into the tie through the opening of said tie plate and a head spaced above the tie plate, a fulcrum member seated on said tie plate and having an opening through which said stem extends, a retaining member having its inner end bearing on the upper surface of said base flange and being fulcrumed adjacent its outer end on said fulcrum member, said retaining member also having an opening therein through which said stem extends, and a coil spring surrounding said stem and acting on said retaining member to press the same against said fulcrum and said base flange, said retaining member sloping downwardly and inwardly toward said base flange such that when the convolutions of said spring are compressed solid at one side of said screw spike they will remain spaced apart at the other side of the screw spike to permit rocking of said upper clamp member on said fulcrum member.

5. In a rail fastening, a tie, a tie plate on said tie and having an opening therein, a rail having a base flange resting on said tie plate, a screw spike having a stem extending into the tie through the opening of said tie plate and a head spaced above the tie plate, a fulcrum member seated on said tie plate and having an opening through which said stem extends and a fulcrum portion located wholly on the side of said stem remote from said rail and extending a substantial distance above the tie plate, a retaining member having one end fulcrumed on said fulcrum portion and at its other end having a downwardly curved bearing portion engaging the top surface of said base flange, said retaining member also having an opening therein through which said stem extends, and a spring surrounding said stem and acting on an intermediate portion of said retaining member to press the latter against said fulcrum portion and said base flange.

6. In a rail fastening of the character described, a tie, a tie plate on said tie and having a rail-gauging shoulder thereon and an opening therein adjacent said shoulder, a rail resting on said tie plate and having a base flange adjacent said shoulder, a screw spike having a stem extending into the tie through the opening of said tie plate and a head spaced above the tie.

plate, a fulcrum member seated on said tie plate and having an opening through which said stem extends and a fulcrum portion located wholly on the side of said stem remote from said rail and extending a substantial distance above said shoulder, a retaining member having one end fulcrumed on said fulcrum portion and at its other end having a downwardly curved bearing portion arching over said shoulder and engaging the top surface of said base flange, said retaining member having an opening in an intermediate portion through which said stem extends, and a spring surrounding said stem and acting on said intermediate portion of the retaining member to press the latter against said fulcrum portion and said base flange.

7. In a rail fastening of the character described, a tie, a tie plate on said tie and having an opening therein, a rail having a base flange resting on said tie plate, a screw spike having a stem extending into the tie through the opening of said tie plate and a head spaced above the tie plate, a fulcrum member seated on said tie plate and comprising integrally connected portions including a laterally extending portion having an opening through which said stem extends and an upright fulcrum portion extending axially along the stem on the side thereof remote from the rail, a downwardly and inwardly sloping retaining member having its outer end rockable on said upright fulcrum portion and having a bearing portion at its inner end engaging the top surface of said base flange, said retaining member also having an opening therein through which said stem extends, and a coil spring surrounding said stem and pressing on said retaining member.

8. In a rail fastening of the character described, a tie, a tie plate on said tie and having an opening therein, a rail having a base flange resting on said tie plate, a screw spike having a stem extending into the tie through the opening of said tie plate and a head spaced above the tie plate, a fulcrum member seated on said tie plate and comprising integrally connected portions including a laterally extending portion having an opening through which said stem extends and an upright fulcrum portion extending axially along the stem on the side thereof remote from the rail, a retaining member having its outer end rockable on said upright fulcrum portion and having a bearing portion at its inner end engaging the top surface of said base flange, and a coil spring surrounding said stem and pressing on said retaining member, said upright fulcrum portion having a fulcrum recess in the upper end thereof and said retaining member having a reduced portion at its outer end engaging in said fulcrum recess.

9. In a rail fastening of the character described, a tie, a tie plate on said tie and having an opening therein which includes an extension portion, a rail having a base flange resting on said tie plate, a screw spike having a stem extending into the tie through the opening of said tie plate and a head spaced above the tie plate, a fulcrum member seated on said tie plate and comprising integrally connected portions including a laterally extending portion having an opening through which said stem extends and an upright fulcrum portion extending axially along the stem on the side thereof remote from the rail, a retaining member having its outer end rockable on said upright fulcrum portion and having a bearing portion at its inner end en-

gaging the top surface of said base flange, said retaining member also having an opening through which said stem extends, and a coil spring surrounding said stem and pressing on said retaining member, said upright fulcrum portion having a reduced portion at its lower end engaging in the extension portion of said tie plate opening.

10. In a rail fastening of the character described, a tie, a tie plate on said tie and having an opening therein, a rail having a base flange resting on said tie plate, a screw spike having a stem extending into the tie through the opening of said tie plate and a head spaced above the tie plate, a fulcrum member seated on said tie plate and comprising integrally connected portions including a laterally extending portion having an opening through which said stem extends and an upright fulcrum portion extending axially along the stem on the side thereof remote from the rail, a retaining member having its outer end rockable on said upright fulcrum portion and having a bearing portion at its inner end engaging the top surface of said base flange, said retaining member also having an opening through which said stem extends, and a coil spring surrounding said stem and pressing on said retaining member, said laterally extending portion having downwardly deflected lugs which engage the edge of said base flange at points spaced therealong.

11. In a rail fastening of the character described, a tie, a tie plate on said tie and having an opening therein which includes an extension portion, a rail having a base flange resting on said tie plate, a screw spike having a stem extending into the tie through the opening of said tie plate and a head spaced above the tie plate, a fulcrum member seated on said tie plate and comprising integrally connected portions including a laterally extending portion having an opening through which said stem extends and an upright fulcrum portion extending axially along the stem on the side thereof remote from the rail, a retaining member having its outer end rockable on said upright fulcrum portion and having a bearing portion at its inner end engaging the top surface of said base flange, said retaining member having an opening through which said stem extends, and a coil spring surrounding said stem and pressing on said retaining member, said laterally extending portion having downwardly deflected means thereon which engages in the extension portion of said tie plate opening.

12. In a rail fastening of the character described, a tie, a tie plate member on said tie, a rail member having a base flange resting on said tie plate member, a fastener connected with said tie and having a headed stem projecting through an opening of said tie plate member, a two-piece clamp comprising an upper piece overlapping said base flange for holding said rail member against said tie plate member and a lower piece forming a fulcrum for said upper piece, said upper and lower pieces having substantially aligned openings through which said stem extends and said lower piece having portions cooperating with one of said members for preventing turning of the clamp pieces about said stem, and a coil spring surrounding said stem and applying downward pressure to said clamp pieces so as to cause said upper piece to apply pressure to said flange and said lower piece to apply pressure to said tie plate member, said upper piece sloping downwardly and inwardly toward said base flange such that when the convolutions of said spring are com-

pressed solid at one side of the fastener they will remain spaced apart at the other side of the fastener to permit rocking of said upper piece on said lower piece

13. In a rail fastening of the character described, a tie, a tie plate on said tie and having an opening therein, a rail having a base flange resting on said tie plate, a screw spike having a stem extending into the tie through the opening of said tie plate and a head spaced above the tie plate, a two-piece clamp comprising a lower clamp member seated on the tie plate and having an upright portion extending along the side of the spike which is remote from the rail and provided at its upper end with a fulcrum portion and an upper clamp member having its outer end rockable on said fulcrum portion and its inner end bearing on the upper surface of said base flange, said upper and lower clamp members having substantially aligned openings through which said stem extends, and a coil spring surrounding said stem and applying a load to said upper clamp member for yieldingly holding said base flange

against said tie plate, said upper clamp member sloping downwardly and inwardly toward said base flange such that when the convolutions of said spring are compressed solid at said remote side of the spike they will remain spaced apart at the inner side of the spike to permit rocking of said upper clamp member on said fulcrum portion.

JACOB RUSH SNYDER.
